United States Patent Office.

ANGUS CAMPBELL, OF DOWNEYVILLE, CALIFORNIA.

Letters Patent No. 85,279, dated December 29, 1868.

IMPROVEMENT IN DERRICKS.

The Schedule referred to in these Letters Patent and making part of the same.

To all whom it may concern:

Be it known that I, ANGUS CAMPBELL, of Downieville, in the county of Sierra, and State of California, have invented a new and improved Derrick; and I do hereby declare that the following is a full, clear, and exact description thereof, which will enable others skilled in the art to make and use the same, reference being had to the accompanying drawing, forming part of this specification, in which—

Figure 1 represents a side view of my improved derrick.

Figure 2 is a detail elevation of the shaft for winding up the cord.

Figure 3 is a detail end view of the truck.

Figure 4 is a detail side view of my improved safety-hook.

Similar letters of reference indicate like parts.

This invention relates to various improvements on derricks, whereby the operation of loading and unloading articles from and into ships and other receptacles can be greatly facilitated.

The invention consists, first, in the use of a truck which slides on the boom; second, in the application of an endless rope for bracing the boom without interfering with the motion of the truck, and without overstraining the topping-lift.

The invention also consists of a safety-hook, for adjusting and suspending the tripping-device.

A represents a mast, of suitable kind, set up on a frame, ship, or other suitable structure.

On it is arranged a boom, B, which can be swung up and down, and which is, at the end, braced by a rope, C, from the top or upper part of the same.

D is a truck, running on the boom B.

It is constructed of a bow, a, to which a top frame, b, and a bottom frame, c, are pivoted, as is clearly shown in figs. 1 and 3.

In the end of each frame, b and c, is a concave roller, d, which fits the boom, as shown. The truck can thus move back and forth on the boom as on a rail, and can, besides, be used as its own brake.

By putting the two front ends, or the rear ends of the pivoted frames b c together, by means of any suitable rope or cord, the rollers at that end will be drawn together, and will constitute a brake for clamping the boom.

The truck can also be strengthened by means of longitudinal ends g' g', pivoted to the two sides of the bow a, and connected at the ends by means of rings h' h'', as shown.

By means of a rope, E, which is attached to the front ends of the truck, and which passes over sheaves e, in front of the boom, the truck can be pulled forward.

By another rope, F, which is fastened with one end to the mast, and which is put around a sheave, f, that is fastened to the back of the truck, the latter can be hauled backward.

C is the topping-lift, fastened with one end to the front end of the boom, passed over a roller, G, that is on the top of the mast, and then down. It serves to brace the boom, and to adjust the same in a horizontal or inclined position.

To take the strain from this rope C, I have arranged a rope, G.

The same is with one end fastened to the front end of the truck, on one side of the same, is then passed around a roller, h, which is attached to the front part of the boom.

The rope is then passed back, in a horizontal direction, over a roller, r, which has its bearings in the lower part of the mast, then up, over a roller, j, on the upper part of the mast, then down, over a sheave, k, which is fastened to and projects from the truck, then up, over a sheave, l, which is suspended from the upper part of the mast, then down, over k, and back again, over rollers j, i, and h, which are arranged on the mast and boom respectively, opposite to the rollers j, i, and before mentioned, and has its other end attached to the other side, near the front end of the truck.

The rollers h h have their bearings in bars or blocks m m, that are fitted to opposite sides of the boom, near the front end of the same, and that are clamped together by means of a metal ball, n.

The rollers i are loosely fitted upon a rod, o, which is fixed in the ring p, by which the boom is fastened to the mast.

The rollers j j have their bearings in arms r r, that project downward from a ring, s, fitted around the upper part of the mast.

The rollers g' and l are suspended from the same ring, s, so that the ropes G and C may follow the motion of the boom, should the same be swung around the mast.

The sheave K is fastened, by means of a hook, H, to a hook or staple, t, which is swivelled to a ball, u, pivoted to the truck, as shown.

The hook H is closed by means of a link, v, and ring w.

The link is pivoted to the end of the hook, and the ring fits loosely around the hook-shank, and rests on a nut, x, which works on the shank of the hook.

From the ring w projects a pin, y, over which the link is fitted, as shown.

The hook is closed, so that it cannot be taken off the staple t when the nut is screwed high enough to prevent the link being taken off the pin y. By lowering the nut, the link can be swung down and the hook opened.

Instead of having the link pivoted to the bill of the hook, it may, as in fig. 4, be pivoted to the pin y, and be fitted over the downward-bent end of the hook H.

The ring w, instead of being supported by the nut x, may be fitted around the same, as shown in fig. 4.

By means of the rope G, the boom will be braced so that a great part of the strain is taken from the top-

ping-lift. If the truck is moved back or forth on the boom, the rope G will adjust itself, and will always brace the boom in the same manner.

In fig. 2 is shown a substitute for the rod o and rollers i. This consists of a crank-shaft, I, which is to have its bearings in lugs projecting from the ring p, and which carries drums z z, with spiral grooves, as shown.

The rope G would be fitted around these drums, and when the shaft is turned the horizontal part of the rope would be wound around them, thereby hauling the truck forward. In this case the rope G would not only serve to brace the boom, but also to haul the truck forward.

J is a tackle-block, suspended, by means of a rope, L, from the truck.

This rope is fastened with one end to a block, M, that is suspended from the truck, is then passed around J, then over the sheave of M, then through tackle-block N, fastened to the front end of the boom, and then down or back to the mast.

By means of the rope L, the weight suspended from the block J can be raised or lowered.

To the block J is pivoted a hook, H, constructed like the hook H above described.

Through it is drawn a chain or rope, O, to the ends of which rings a' b' are respectively attached. The end having the ring b' is drawn through the ring a'.

The ring a' is also fitted through the upper end of a bar or rod, P, to the lower end of which a short arm, c', is pivoted.

To the upper part of the bar P is pivoted a lever, R. The weight to be elevated or conveyed is fastened by drawing the chain O around it, the ring b' is then put

over the arm c', the free end of which is then locked into a notch, forming the lever R, as shown in fig. 1.

The weight is thus firmly secured, and can be raised to any desired height by means of the rope L, and brought over any desired spot by swinging the boom.

When it is to be released, the lever R is swung up by pulling a trip-cord, d', which is attached to the free end of said lever, and passes over a roller, e', on the truck, and one, f', on the mast, as shown. Instead of the truck, a slide of other description may be used on the boom, in connection with my other improvements.

Having thus described my invention,

I claim as new, and desire to secure by Letters Patent—

1. The truck D, consisting of the bow a, swinging frames b c, and concave rollers d, substantially as herein shown and described.

2. The rope G, when arranged as described, to brace the boom, by being fastened to the truck sliding thereon, for the purpose of relieving the topping-lift C, as specified.

3. The hook H, having the nut z, ring w, and link v, arranged substantially as and for the purpose herein shown and described.

4. The chain O, bar P, lever R, and arm c', in combination with the hook H, nut z; ring w, and link v, arranged as described for the purpose specified.

The above specification of my invention signed by me, this 31st day of March, 1868.

ANGUS CAMPBELL.
